United States Patent Office

Des. 216,510
Patented Jan. 27, 1970

216,510

COUCH FOR USE IN SUNTANNING

Carl R. Meyer, 2512 E. Vine St.,
West Covina, Calif. 91790

Filed Aug. 2, 1968, Ser. No. 13,016

Term of patent 14 years

Int. Cl. D6—01

U.S. Cl. D15—11

FIG. 1.

FIG. 2.

FIG. 3.

FIG. 4.

FIGURE 1 is a front perspective view of a suntanner showing my new design;

FIGURE 2 is a foot-end elevational view thereof;

FIGURE 3 is a plan view thereof; and

FIGURE 4 is a head-end elevational view thereof.

I claim:

The ornamental design for a couch for use in suntanning, as shown.

References Cited

House and Garden, April 1960, bridging, pp. 194–195,
"Sun Scoop," by W. Wes Williams.
House and Garden, April 1960, p. 195, lounge at upper center, by Brown-Jordan Co.

BRUCE W. DUNKINS, Primary Examiner